PERCUSSIVE TOOL FOR SCALING BOILER SURFACES

Filed March 30, 1921

UNITED STATES PATENT OFFICE.

PERCY GILBERT HANDOLL, OF LEWISHAM, LONDON, ENGLAND.

PERCUSSIVE TOOL FOR SCALING BOILER SURFACES.

Application filed March 30, 1921. Serial No. 457,129.

To all whom it may concern:

Be it known that PERCY GILBERT HANDOLL, of 68 Wisteria Road, Lewisham, London, England, has invented certain new and useful Improvements in Percussive Tools for Scaling Boiler Surfaces, of which the following is a specification.

This invention relates to percussive tools for scaling boiler tubes or other surfaces, and has for its object to provide a pneumatic or fluid pressure tool which shall be simple in construction and reliable in operation. My improved tool comprises two main parts or members, viz., an inner member which serves as a guide and is held firmly with its front end against the tube, plate, or other surface during the operation of the tool, and an outer member or percussive body mounted to reciprocate longitudinally upon the inner member and formed with cutting edges on its forward end.

An annular chamber or space is formed between the inner member and the percussive body mounted thereon to which the pressure fluid is admitted continuously and operates to reciprocate the percussive body as hereinafter described.

The percussive body is cylindrical in shape and its ends which have circular openings and fit around parts of the inner member of different diameters, constitute the ends of the pressure chamber and are so dimensioned that the forward end presents a larger area to the action of the pressure fluid than the rear end. In consequence of this difference the tendency of the pressure fluid is to force the percussive body forward, and means are provided whereby the pressure on the forward end of the percussive body is relieved when that body approaches the limit of its forward stroke, allowing the pressure exerted on the rear end to effect the return stroke. For this purpose exhaust apertures or outlets are uncovered by the percussive body near the end of the forward stroke, and the front and rear portions of the annular pressure chamber or space are separated more or less or communication between them is cut off momentarily by an enlargement or collar on the inner member moving into a part of the chambered interior of the percussive body which fits more or less closely around the collar.

In the accompanying sheet of illustrative drawings:

Fig. 1 is a longitudinal section of a scaling tool constructed according to this invention.

Fig. 2 is a side elevation of the same and Figs. 3 and 4 are transverse sections on the lines 3—3 and 4—4 respectively of Fig. 1.

As shown, a percussive body *a* of cylindrical shape and formed with a serrated cutting end face *a'* is supported and guided upon the inner member *b* the forward end *b'* of which is adapted to be held against the work whilst the other end is fitted with a hollow T piece *c* coupled by a sleeve *c'* with a tubular handle *d* which is coupled in turn with a flexible tube for the supply of compressed air or other pressure fluid.

The inner member *b* is bored or otherwise formed with an axial inlet *e* for the pressure fluid extending from its rear end and terminating in a radial passage or passages *f* located at some distance from the rear end behind an annular shoulder or enlargement *b*². Between the percussive body or cylinder *a* and the inner member *b* is formed an enclosed annular space or chamber *g* which in all positions of the percussive body *a* remains in communication with the pressure fluid inlet *e* through the radial passage or passages *f* referred to. At its front end is an enlarged annular chamber or space *g'*. The percussive body *a* is free to reciprocate on the inner member *b* under the action of the pressure fluid, the range of movement in either direction being limited by the annular externally grooved shoulder or enlargement *b*² on the inner member which fits the chamber *g* but is smaller than the chamber *g'*. The enlargement *b*² separates or cuts communication between the front and rear annular spaces *g* and *g'* as the outer member descends and the enlargement *b*² enters the space *g*. The front chamber *g'* is open to the exhaust *h* along the part *b'* when the outer member is in its lower position. That portion *b'* of the inner member *b* which is in front of the shoulder or enlargement *b*² is of smaller diameter than the portion behind the shoulder, and the front end *a*² of the percussive body which is subjected to the pressure in the chamber during the forward or working stroke is of greater area

than the rear end a^3 of the same which is constantly subjected to pressure. The rear end becomes effective to actuate the percussive body only at the end of the forward 5 stroke when the fluid pressure operating on the larger end a^2 is exhausted through outlets at that end provided by forming flattened portions h or grooves on the reduced end of the inner member or in other ways.

10 In order to permit of the mounting of the percussive body or cylinder over the inner member the rear end a^3 is formed of a removable ring which is screwed into position and secured by a locking pin held in position by a wire ring a^4 . The inlet end of the bore e in the inner member b is internally screw-threaded to receive the T piece c for the connection of the handle and pressure fluid supply tube.

15 20 A valve i is provided in the hollow T piece c for admitting and shutting off the pressure fluid and the valve spindle is fitted with a detachable mushroom head i' arranged to serve the dual purpose of controlling the 25 valve and applying pressure to the tool. When pressure is applied to the head i' by the hand of the operator the valve is opened against the action of a spring j which tends to keep the valve closed.

30 35 In operation, the percussive body or cylinder a rests at starting in the position shown by broken lines in Fig. 1 the forward end b' of the member b being held against the work. On opening the valve i by pressing with

40 45 the hand on the head i' as described the pressure fluid is admitted through the inlet passages e, f to the chamber g . The passage g' being closed by being entirely below the enlarged portion b^2 of the inner member, the 50 fluid acts only against the rear end a^3 of the chamber and forces the percussive member a back into the position shown in full lines in Figs. 1 and 2.

55 60 In this position the enlarged or ported part g' of the cylinder a is put in free communication with the inlet passages f admitting the pressure fluid to the front end of the chamber g where operating on the larger area a^2 at the front end of the percussive body, it forces that body forward causing it to strike a sharp blow against the work. As it approaches the end of this stroke the end a^2 of the chamber passes the upper end of the exhaust port or outlet formed by the

flattened portion h and the pressure then 55 escapes through said outlets. The percussive body or cylinder is now at the starting position again and the passages g' have been again closed by the enlarged part b^2 so that the cycle is repeated automatically. 60

I claim:—

1. An improved percussive tool operated by fluid pressure and comprising an inner member adapted to be held firmly against the work, an outer member forming the percussive body mounted to reciprocate longitudinally on the inner member and forming with the inner member an annular pressure chamber or space, against the opposite ends of which the pressure fluids acts to effect the forward and return strokes of the percussive body, and means controlling the supply, distribution and exhaust of the pressure fluid substantially as described. 70

2. An improved percussive scaling tool operated by fluid pressure and comprising an inner stationary member having passages for the pressure fluid, an outer reciprocatory percussive body guided on the inner member and co-operating therewith to distribute the pressure fluid, and having cutting edges on the forward end thereof a hollow handle with pressure fluid supply connection coupled with the rear end of the inner member and a valve in the supply connection fitted with a head adapted to serve for opening the valve and applying hand pressure to the tool. 80

3. An improved percussive tool including an inner member bored axially and radially with pressure fluid passages, an outer reciprocating member constituting the percussive body and forming a pressure chamber around the inner member receiving pressure fluid through said passages, the relative dimensions of the ends of the pressure chamber being such that the forward end presents a larger area to the action of the pressure fluid than the rear end, means on the inner member for separating the front and rear portions of the pressure chamber and opening the forward end to the atmosphere when the percussive body approaches the end of the forward stroke substantially as and for the purpose described. 100

In testimony whereof he affixes his signature.

PERCY GILBERT HANDOLL.
